UNITED STATES PATENT OFFICE.

JAMES RICHARDS, OF BALTIMORE, MARYLAND.

AEROPLANE.

1,325,377.

Specification of Letters Patent. Patented Dec. 16, 1919.

Application filed March 21, 1919. Serial No. 283,992.

To all whom it may concern:

Be it known that I, JAMES RICHARDS, a citizen of the United States, residing at Baltimore, State of Maryland, have invented 5 a new and useful Aeroplane, of which the following is a specification.

This invention relates to aeroplanes and more especially to means whereby a quick ascent and descent of a machine can be effected by bodily shifting the propeller relative to the tail portion of the fuselage, one of the objects of the invention being to provide an aeroplane body formed of front and rear sections hingedly connected and 15 having means under the constant control of the aviator whereby the two sections can be shifted relative to each other about a transverse axis, thereby to allow the nose portion of the machine to be pointed upwardly 20 while the remainder of the machine is supported by the running gear on the ground, and facilitating the abrupt ascent of the machine from a limited area.

With the foregoing and other objects in view which will appear as the description proceeds, the invention consists of certain novel details of construction and combinations of parts which will be hereinafter more fully described and pointed out in the 30 claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings—

40 Figure 1 is a view partly in side elevation and partly in section of the aeroplane, one of the positions of the nose portion being shown by dotted lines.

Fig. 2 is an enlarged vertical transverse section on line 2—2, Fig. 1.

Fig. 3 is a view in diagram showing how the cam operates to shift the nose.

Referring to the figures by characters of reference, 1 designates the rear or tail portion of the body of the aeroplane, the same being provided with running gear 2 and carrying a rudder 3 which can be operated in suitable manner, as by means of foot pedals 4 operating an endless belt 5 engaging a wheel 6 on the shaft 7 of the rudder.

A transverse shaft 8 is journaled in the section 1 and has a gear 9 thereon adapted to be rotated by any suitable means such as a gear 10 secured to a post 11 having a hand wheel 12. Secured to the shaft 8 so as to 60 rotate therewith are cam arms 13 having rack teeth 14 and formed in each arm is a slot 15.

The front section 16 of the aeroplane body carries the sustaining plane 17, the propeller 18 and the engine, not shown. This section is hingedly connected at the top of the rear end thereof to the section 1, as shown at 19. Extending rearwardly from each side of the section 16 is a pair of 70 arms 20, the arms of each pair being connected by a pin 21. The arms 20 are located at each side of the respective cam arms 13 and the pins 21 are slidably mounted in the slots 15. Journaled between the arms 20 of each pair is a gear 22 constantly in mesh with the teeth on the adjacent arm 13.

From the foregoing it will be apparent that when the arms 13 are swung downwardly they will rotate the gears 22 and 80 thrust therethrough against the section 16, causing it to swing upwardly, as indicated by dotted lines, in Fig. 1, so that the rotating propeller will exert an upward pull upon the aeroplane and cause the machine 85 to move upwardly at an abrupt angle. By reversing the movement of the arms 13 the front section 16 will be moved downwardly. The action of the arms on the nose of front section 16 of the machine has been indicated 90 in diagram in Fig. 3.

What is claimed is:—

1. The combination with an aeroplane body including a rear section, and a front section hingedly connected to and adapted 95 to swing upwardly and downwardly relative to the rear section, of a cam arm mounted for oscillation within the rear section, means on the front section for slidably engaging the cam arm, revoluble 100 means on the front section for receiving the thrust from the cam arm, and means for actuating the cam arm.

2. The combination with the hingedly connected front and rear sections of an aeroplane body, of longitudinally slotted cam arms mounted on the rear section, means for swinging said arms in unison, means upon the front section for sliding engagement with the arms, and projecting into the slots, 110

and revoluble means on the front section for receiving the thrust from the arms.

3. The combination with hingedly connected front and rear sections of an airplane body, of a shaft journaled in the rear section, longitudinally slotted arms connected to the shaft and constituting cams, each arm having a longitudinal slot, rack teeth upon each arm, gears freely revoluble 10 on the front section and engaged by and adapted to receive thrust from the toothed

arms, and means upon the front section and projecting into the slots in the arms for holding the arms and gears in mesh.

In testimony that I claim the forgoing as 15 my own, I have hereto affixed my signature in the presence of two witnesses.

JAMES RICHARDS.
